RAILWAY HAND BRAKE

Filed June 13, 1928

2 Sheets-Sheet 2

A detailed technical drawing of a mechanical assembly, possibly a gear mechanism. The drawing is labeled with various numbers, likely referring to parts or steps in a patent application. The assembly includes a large outer gear (19) with a wavy profile, a smaller gear (22) with a central hole, and a central hub (21) with a pin (20). A spring (37) is attached to a lever (36) which is connected to a pin (38). A small gear (46) is mounted on a shaft (31) which is supported by a bearing (25). The assembly is shown in cross-section, revealing internal components like a pin (32), a square slot (28), and a lever (34) with a slot (35). The drawing is annotated with numbers 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, and 47.

UNITED STATES PATENT OFFICE

RICHARD W. BURNETT, OF CHICAGO, ILLINOIS

RAILWAY HAND BRAKE

Application filed June 13, 1928. Serial No. 285,023.

This invention relates to manually operated apparatus for setting and releasing the brakes of a railway car, and particularly to brake apparatus of the type involving a chain or other flexible element which is wound upon a drum or similar revoluble member for setting the brake shoes against the wheels of the car. The hand brake apparatus of my invention is suitable for use upon box cars, hopper cars, gondola cars, flat cars and other types of railway cars.

The invention is concerned particularly with the mechanism for revolving the winding drum to set the brakes, for holding the winding drum in the brake setting position and for releasing it to relieve the pressure of the brake shoes on the car wheels; and the principal object is to provide a simple strong and durable mechanism for setting and releasing the brakes which can be operated quickly, easily and conveniently, for example in switching and making up trains, or cutting a car from the train, without the risk to life and limb of the brakeman, or injury to the car and its cargo, frequently incurred in the operation of hand brakes of the type commonly used heretofore in railway freight car service.

The invention is illustrated in certain preferred embodiments in the accompanying drawings in which

Fig. 1 is a fragmentary end elevation of a railway car provided with the hand brake apparatus of my invention.

Fig. 2 is a longitudinal sectional view on line 2—2 of Fig. 1, the scale being enlarged.

Fig. 3 is a sectional view on line 3—3 of Fig. 2.

Fig. 4 is a detail sectional view on the plane of Fig. 3 illustrating the position to which the pawl is moved during the brake setting movements of the winding drum and ratchet wheel, and

Fig. 5 is a view similar to Fig. 4 showing the pawl moved to a position to be disengaged from the ratchet wheel.

Referring to the drawings, 10 designates the end wall of a railway box car. The hand brake mechanism comprises a rocking member or bellrank 11 shown as pivotally sup-

ported at 12 on a bracket 13 secured to the underside of the end sill 14 of the car. The brake rigging by which is included the system of brake shoes, beams, connecting rods, et cetera, arranged under the deck of the car, and ordinarily operated by air pressure, is connected by suitable means (not shown), for example by a chain, with the rocking member 11, for operation of the brakes by the hand braking apparatus.

Pivotedly secured at 15 to the outer end of the rocking member 11 is a rod 16 having a forked lower end 17 and provided at its upper end with a clevis 18 for a chain, or other flexible element 19, which is attached at 20 to a winding drum 21 carried on a shaft 22 revolvably mounted in bearings in the front and rear walls 23, 24 of a housing 25 secured to the end wall 10 of the car. By the term "chain" as used in the specification and claims hereof, I intend to cover any suitable flexible element, such, for example, as a rope or cable; and by the terms "drum" or "winding drum" I intend any revoluble member on which the chain is wound for taking up slack in the brake rigging and bringing the brake shoes with braking pressure against the wheels of the car. Preferably the drum 21 is provided with a winding surface of sufficient length so that the brakes may be set with less than a single revolution of the drum, the center line of the winding surface being in a single plane. The present invention, however, is not limited to any particular type of winding drum.

Fixed to shaft 22 is a large gear wheel 26 which meshes with a small gear 27 on a shaft 28 revolvably mounted in bearings on the front and rear walls of housing 25, shaft 27 having an extension 29 through the front wall 23 of the housing to which extension is secured a hand wheel 30, preferably of relatively large diameter. Fixed to shaft 28, within the housing, is a ratchet wheel 31, the teeth of which are adapted to be engaged by a pawl 32, this pawl being mounted on an eccentric portion 33 of a shaft 34 revolvably supported in bearings on the walls of the housing and projecting through the front wall 23 thereof. To

the projecting end of shaft 34 is secured a lever 35 for effecting the release of the brakes, in the different ways to be described, through disengagement of the pawl from the ratchet.

5 Guiding means is provided for effecting the disengagement of the pawl from the ratchet by rotation of shaft 34 by means of the hand lever 35. The guiding means preferably consists of a slot 36 formed in the pawl 10 and a pin 37 having a fixed position in the casing, which pin extends through slot 36, the pin being of a diameter smaller than the width of the slot. A coiled spring 38 secured at one end to a lug 39 on the pawl and at the 15 other end to a bracket 40 on the wall of the housing tends to keep the tooth 41 of the pawl in engagement with the teeth of the ratchet 31. The pawl is also preferably formed with a tail-piece 42 which comes into contact with 20 the teeth of the ratchet when the pawl is shifted to its position of release, stopping the lever when moved to this position. A stop pin 46 is arranged to limit the movement of the lever in the other direction.

25 Fig. 3 illustrates the positions of the parts of the apparatus after the brakes have been set. Fig. 4 illustrates the manner in which the pawl rides over the teeth of the ratchet during the setting of the brakes. The pawl 30 oscillates on the eccentric 33 sufficiently so that its tooth 41 will clear the teeth of the ratchet. This is possible because of the width of slot 36 in proportion to the diameter of the guide pin 37.

35 Fig. 5 illustrates the positions of the pawl and operating lever on movement of the lever to the releasing position, that is when the lever is swung from its right hand position (Fig. 3) to the left-hand position (Fig. 5). 40 This movement of the lever gives the eccentric 33 an angular change of position of approximately 180°. Engagement of the upper surface 43 of slot 36 with the pin 37 compels the pawl to shift, as eccentric 33 is rotated, 45 with a cam action which raises the tooth 41 on the pawl from the ratchet wheel and brings the tail-piece 42 of the pawl into engagement with the teeth of the ratchet. Said tail portion 42, by reason of the weight of the lever 50 35, bears frictionally against the ratchet wheel. Obviously this frictional engagement can be increased by exerting downward pressure on the lever and thereby retarding reverse movement of the ratchet wheel. When 55 the lever 35 is moved back from left to right spring 38 insures the reengagement of the pawl with the ratchet.

60 *Operation.*—In setting and releasing the brakes the brakeman stands upon the platform 44 on the end of the car (Fig. 1) and holding on to one of the rungs 45 of the end ladder with his left hand (or to some other suitable handhold) and gives the hand wheel 30 a spin or twirl in the clockwise direction 65 with his right hand. A single spin of the

wheel will ordinarily be sufficient to take up all of the slack in the brake rigging and the lost motion in the hand brake apparatus and set the brake shoes against the wheels of the car with some braking pressure. To completely set the brake it is necessary for the brakeman to take another hold on the hand wheel with his right hand, grasping either the rim or one of the spokes as most convenient, and give the wheel further movement of rotation in the clockwise direction. These movements of the hand wheel wind the chain 19 on the drum 21, as shown in Fig. 3, the pawl 32 oscillating on the center *a* of the eccentric 33 so as to ride over the teeth of the ratchet wheel as the latter revolves, as shown in Fig. 4.

To obtain an instantaneous release of the brakes the brakeman, still maintaining his hold on the ladder rung or other handhold with his lefthand, grasps the lever 25 with his right and swings the lever from the position shown in Fig. 3 to the position shown in Fig. 5. This shifts the center *a* of the eccentric backwardly away from the ratchet, that is to the other side of the axis of shaft 34 which is indicated in the drawings, at *b*. The tooth 41 of the pawl is forced out of engagement with the ratchet wheel through the camming action taking place between the slotted portion of the pawl and the fixed pin 37. The release of the brakes may be complete or, if desired, the lever may be given quick movement first to the left and then to the right 100 so as to bring about a partial release of the brake followed by a re-engagement of the pawl with the ratchet wheel. For drifting the car, for example, the lever 35 may be turned to the left to a position a trifle beyond the vertical, which will be insufficient to disengage tooth 41 from the ratchet wheel 31. The brakeman then grasps the hand wheel 30 and gives the wheel a slight turn clockwise, that is in the brake setting direction, to relieve the pressure between the ratchet and pawl. The lever now falls to the position illustrated in Fig. 5 by its weight, the lever being heavy enough to overcome the pull of spring 38, leaving the release of the brake under the control of the brakeman through manipulation of the hand wheel, or for drifting, the brakeman may manipulate the wheel with one hand and shift the lever with the other.

105 While I have described my invention in a preferred embodiment, the possibility of modification is recognized and I desire to cover by patent all modifications and variations within the scope of the appended claims.

110 I claim:

1. In mechanism for holding the brakes of a railway car in set position and for releasing them, the combination of a ratchet, a pawl, an eccentric upon which the pawl is revolvably supported, means for rotating the eccentric, 115 120

125

130

and guiding means cooperating with the eccentric to effect the engagement of the pawl with, and its disengagement from, the ratchet at different angular positions of the eccentric.

- 5 2. In mechanism for holding the brakes of a railway car in set position and for releasing them, the combination of a ratchet, a pawl, an eccentric upon which the pawl is revolubly supported, means for rotating the eccentric, 70 and guiding means which effects the engagement of the pawl with, and its disengagement from, the ratchet at different angular positions of the eccentric, while permitting the pawl to ride over the teeth of the ratchet 75 10 when the latter is given a brake-setting movement.

3. In mechanism for holding the brakes of a railway car in set position and for releasing them, the combination of a ratchet, a 20 pawl, an eccentric upon which the pawl is revolubly supported, a lever for rotating the eccentric, and guiding means cooperating with the eccentric to effect the engagement of the pawl with, and its disengagement from, the ratchet at different angular positions of the eccentric. 80

4. In mechanism for holding the brakes of a railway car in set position and for releasing them, the combination of a ratchet, a 25 pawl, means which tends to keep the pawl in engagement with the ratchet, an eccentric upon which the pawl is revolubly supported, means for rotating the eccentric, and guiding means cooperating with the eccentric effect 35 the engagement of the pawl with, and its disengagement from, the ratchet at different angular positions of the eccentric. 95

5. In mechanism for holding the brakes of a railway car in set position and for releasing them, the combination of a ratchet, a pawl, a spring which tends to keep the pawl in engagement with the ratchet, an eccentric upon which the pawl is revolubly supported, means for rotating the eccentric, and guiding 45 means cooperating with the eccentric to effect the engagement of the pawl with, and its disengagement from, the ratchet wheel at different angular positions of the eccentric. 100

6. In mechanism for holding the brakes of a railway car in set position and for releasing them, the combination of a ratchet, a pawl, an eccentric upon which the pawl is revolubly supported, means for rotating the eccentric, and guiding means which effects the engagement of the pawl with, and its disengagement from, the ratchet at different angular positions of the eccentric, comprising a slot in 55 the pawl and a stationary pin extending into said slot. 105

60 7. In mechanism for holding the brakes of a railway car in set position and for releasing them, the combination of a ratchet, a pawl, an eccentric upon which the pawl is revolubly supported, means for rotating the eccentric, and guiding means which effect the en- 110

gagement of the pawl, with and its disengagement from, the ratchet at different angular positions of the eccentric while permitting the pawl to ride over the teeth of the ratchet when the latter is given a brake setting move- 70

75 8. In mechanism for holding the brakes of a railway car in set position and for releasing them, the combination of a ratchet wheel, a pawl to engage the ratchet wheel having a tail-piece which bears against the ratchet wheel in the disengaged position of the pawl, an eccentric upon which the pawl is revolubly supported, means for rotating the eccentric, and guiding means which effects the engagement of the pawl with, and its disengagement from, the ratchet at different angular positions of the eccentric. 80

9. In hand brakes for railway cars, the combination with hand power mechanism operable in one direction to set the brakes, of means for retarding reverse movement of said power mechanism comprising a member pivoted to bear frictionally against a moving part of said mechanism during said reverse movement thereof, an eccentric on which said pivoted member is supported, and means for changing the position of said eccentric to vary the frictional engagement of said pivoted member with said moving part. 95

10. In a hand brake for railway cars, the combination with hand power mechanism operable in one direction to set the brakes, 100 of means for holding the brakes in set position, means for retarding reverse movement of said mechanism comprising a member adapted to be pressed frictionally against a moving part of said mechanism and means for releasing said holding means and varying the frictional engagement of the retarding means comprising an eccentric, a lever for changing the position of said eccentric whereby in one position the holding member is disengaged from said power mechanism and the retarding member is pressed frictionally against said moving parts. 110

11. In mechanism for holding the brakes of a railway car in set position and for releasing them, the combination of a ratchet wheel, a pawl, a rotatable shaft, means on said shaft for supporting the pawl eccentric to the axis of rotation of said shaft, a hand lever on said shaft for moving the pawl supporting means to different angular positions, and guiding means which effect engagement of the pawl with, and its disengagement from, the ratchet at different angular positions of said pawl supporting means. 115

12. In hand brakes for railway cars, the combination with hand power mechanism including a horizontally disposed power shaft and a hand wheel thereon operable in one direction to set the brakes, of mechanism for

holding the brakes in set position and for releasing them, comprising a ratchet wheel on said power shaft, a pawl positioned to engage the upper portion of said ratchet wheel, an eccentric upon which the pawl is revolvably supported, means for rotating the eccentric, and guiding means which effect the engagement of the pawl with, and its disengagement from, the ratchet at different angular positions of the eccentric while permitting the pawl to ride over the teeth of the ratchet wheel when the hand power mechanism is given a brake-setting movement.

13. In a hand brake for railway cars, the combination with hand power mechanism including a horizontally disposed power shaft and a hand wheel on said shaft operable in one direction to set the brakes, of means for holding the hand power mechanism in and releasing it from its brake setting position comprising a ratchet wheel on said power shaft, a pawl positioned to engage the top portion of said ratchet wheel, a trip shaft, pawl supporting means on said trip shaft for supporting the pawl on an axis eccentric to the axis of said trip shaft, a hand lever on said trip shaft, and operable in a plane between the hand wheel and said ratchet wheel, and guiding means which effect the engagement of the pawl with, and its disengagement from, the ratchet wheel at different angular positions of said pawl supporting means.
